UNITED STATES PATENT OFFICE.

HENRY G. HUNTER, OF MONTREAL, QUEBEC, CANADA.

BUILDING.

1,282,583.

Specification of Letters Patent. Patented Oct. 22, 1918.

Application filed February 8, 1918. Serial No. 216,113.

To all whom it may concern:—

Be it known that I, HENRY GRANVILLE HUNTER, a resident of the city of Montreal, Province of Quebec, Dominion of Canada, a citizen of the United States, have invented certain new and useful Improvements in Buildings; and I do hereby declare that the following is a full, clear, and exact description thereof.

10 My invention relates particularly to buildings for accommodating a number of automobiles and more particularly for the accommodation of automobiles owned by different people.

15 Heretofore considerable damage to cars has resulted from parking in public garages owing to the fact that an attendant was required at all times to admit tenants and allow cars to be taken out; and damage was

20 frequently caused in parking or running out by interference of the moving car with those standing about. Furthermore, inconvenience has been experienced by the drivers of the cars after having entered the building in

25 entering and leaving the garages or stalls. My invention has for its object to overcome these inconveniences and at the same time provide a garage building which will afford all the advantages of a private garage for 30 each tenant and avoid the necessity of the employment of an attendant, and at the same time economize both space and material.

To this end the invention may be said briefly to consist of a garage structure comprising a series of individual private garages and a driveway common to the series, the garages being disposed in oblique arrangement relatively to the driveway; while the door of each garage is of a particular type adapted to be accommodated in the space presented by the front of each private garage and the exterior of an adjoining garage the corner of which is caused to protrude owing to the particular angular arrangement.

For full comprehension, however, of my invention, reference must be had to the accompanying drawings in which similar reference characters indicate the same parts, 50 and wherein:

Figure 1 is a part side elevation and part sectional view of garage structure erected according to my invention;

Fig. 2 is a plan view of the first street 55 floor, section being taken on line 2—2 Fig. 1;

Fig. 3 is a front elevation of the structure;

Fig. 4 is an enlarged detail plan view of one of the private garages illustrating more particularly the interior arrangement and door structure;

Fig. 5 is a similar view to Fig. 2 of the floors above the first floor; and

Fig. 6 is a front elevation of one of the private garages illustrating the doors in closed position.

The structure is preferably of rectangular plan view and of sufficient width to accommodate four series of private garages indicated at *g*, *h*, *i* and *j*. The walls *m* and *n* of the structure are preferably parallel and the interior is divided by a longitudinal partition between each end of which and the ends *p* and *q* of the structure spaces are provided for elevators *r*.

My individual garages are arranged in series along each side wall and the opposite sides of the partition and the relative width of the structure and length of the individual garages of each series, transversely to the structure, are such that a pair of longitudinal spaces *t* are provided between the middle and side garages, such spaces being slightly greater in width than the width of the individual garage. These comparatively narrow longitudinal spaces serve as driveways common to all the individual garages at each side of the structure, and I make provision for this relatively narrow driveway by including the garages of each series toward one end of the structure, greatest economy in space being obtained by inclining the garages of all four series toward the same end of the structure, entrances *u* being formed in that end wall to communicate with the respective driveways, while outlets *v* are correspondingly located in the opposite end. This particular oblique arrangement of the garages permits a car to be driven into the structure through one of the entrances, along the common driveway to the particular garage in which it is to be stalled, and it can be turned into this garage without the necessity of maneuvering, but with the door open can be turned in at a wide curve. When leaving the garage the car is backed out into the driveway in the same wide curve until it can be headed along the driveway toward the outlet, when it can be run out also without maneuvering.

The oblique arrangement of the garages also has the effect of causing one corner *w*

of each garage to protrude thus forming space α at the front of each garage to accommodate the door. These doors are of the folding type and each consists of two members 2 and 3 respectively hinged together as at 4 and the opposite edge of the member 3 being hinged to the side of the door frame 5 at the corner w . The dimensions of the garages and the angle of inclination are such that the protruding corner w is of sufficient depth to accommodate the door when folded in open position. In this manner the common driveway is not in any way obstructed by the door when thrown open, neither is the interior of the garage encroached upon.

In order to accommodate oil, cleaning cloths, tools, etc., a closet 10 is formed in the innermost corner and preferably provided with lock and key in order that when the car is taken out, the door of the garage may be left open to facilitate returning the car.

The structure illustrated has three floors, the first, 12, the street floor, and the second 13, being equipped with the series of oblique garages, while the top floor 14, is left open to permit the cars being parked without individual garages, this top floor being more in the nature of a public garage, whereas the individual garages of the first and second floors are of the nature and afford all the advantages of private garages. Communication is effected between the floors by the elevators 7 and staircases 20. In order to facilitate washing the cars, washing stands 25 with proper washing drainage facilities are provided at the entrance end

of the structure, and the individual garages are similarly equipped, a common drainage pipe 50 being located at each side of the building and branches 51 leading from the garages to them.

For purposes of ventilation a ventilating system communicates with the respective garages. The system indicated consists of pipes 30 communicating with all garages in vertical line and having branches 31 leading to the top of the garages; while the doors are preferably raised a short distance from the floor, by casters 32, to provide space to admit air, and air is also admitted by openings 33 in the wall over the doors and communicating with the passages.

What I claim is as follows:

A garage structure comprising a building containing a series of individual private garages and a driveway common to the same, the said garages being disposed in oblique arrangement relatively to the driveway, the angle of obliquity of all the garages being inclined toward one and the same end of the series, the respective garages each having a corner protruding into the driveway and doors for closing the garages and constructed and arranged to be accommodated within the space presented by the end of each individual garage, and the protruding corner of the next individual garage.

In testimony whereof I have signed my name to this specification in the presence of two witnesses.

HENRY G. HUNTER.

Witnesses:

GORDON G. COOKE,

WILLIAM J. C. HEWETSON.
